UNITED STATES PATENT OFFICE.

JAMES VINSON, OF TUNNEL HILL, ILLINOIS.

MOTOR.

1,078,074.

Specification of Letters Patent. Patented Nov. 11, 1913.

Application filed April 13, 1912. Serial No. 690,625.

To all whom it may concern:

Be it known that I, JAMES VINSON, a citizen of the United States, residing at Tunnel Hill, in the county of Johnson and State 5 of Illinois, have invented a new and useful Motor, of which the following is a specification.

This invention relates to air motors of that type designed to be operated by the 10 constantly moving current of air passing through an upwardly extending flue.

The invention is more particularly an improvement upon the structure disclosed in Patent No. 758,226, issued to me on April 15 26, 1904, and its principal object is to provide means whereby the hood which is mounted for rotation at the outlet end of the flue, is protected from rain and snow without interfering with the proper circulation 20 of air.

A further object is to provide an improved housing for a portion of the apparatus whereby said portion is protected.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed can be made within the scope of what is claimed, without departing from the spirit of the invention.

35 In the accompanying drawings the preferred form of the invention has been shown.

In said drawings:—Figure 1 is a view partly in side elevation and partly in section of the apparatus having the present 40 improvements combined therewith. Fig. 2 is an end elevation.

Referring to the figures by characters of reference 1 designates a casing having an air chamber therein provided with a series 45 of inlet openings, one of which has been indicated at 2 in Fig. 1. A shield 3 is mounted in front of and spaced from each of the openings 2 so as to prevent the direct passage of air into the casing 1 through 50 the opening.

An upwardly extending air shaft 4 is located at any suitable distance from the casing 1 and is connected thereto by a conduit or flue 5 the inlet end of which is preferably flared, as shown at 6 while its outlet 55 end is curved upwardly and opens into the

bottom portion of the air shaft, as shown at 7. An intermediate portion of the flue 5 is offset as shown at 8, and mounted for operation within the flue 5 between said offset portion and the air shaft 4 is a rotor 9 the shaft 10 of which projects beyond the flue 5 and may be provided with a pulley 11 whereby motion may be transmitted to the mechanism to be actuated. 65

A valve, indicated generally at 12, is mounted in the flue 5, preferably adjacent the casing 1 and by means thereof the circulation of air through the flue 5 may be controlled. 70

A head 13 is mounted for rotation on the upper end of the air shaft 4 and carries a hood 14 which overhangs the outlet end of the air shaft and serves to direct air radially from the shaft. This hood carries a vane 75 15 which is so located that the open side of the hood 14 is constantly held in position to discharge the air current from the air shaft 4 in the direction in which the outer air current is moving. 80

Arms 16 are secured to the upper end portion of the shaft 4 and are curved outwardly and upwardly therefrom, the said arms being crossed above the center of the hood and suitably connected so as thus to form a frame 85 for the support of a dome-like shield 17. This shield is so proportioned as to fully protect the hood 14 from rain and snow and it will be apparent, therefore, that there is no danger of the hood being held against rotation by ice which would otherwise form thereon in cold weather. 90

Rails 18 are extended upwardly to the upper portion of the air shaft 4 from the ground or other surface on which the apparatus is mounted and these rails are connected by ladder rungs 19. Thus it will be seen that a person can ascend readily to the hood 14 for the purpose of repairing or cleaning the same. 100

The flue 5 is preferably inclosed in a housing made up of side walls 20 supporting top sections 21. These top sections are preferably removable so that access may be had conveniently to the flue 5. 105

It is to be understood that the air shaft 4 will be of any height desired. Obviously the higher the air shaft the stronger will be the current of air passing therethrough. This is due to the fact that warm air naturally 110 rises. The circulation of air through the apparatus is also produced to an increased ex-

tent when the wind is blowing as the external air current thus sets up a suction through the hood 14. As the air passes from casing 1 and through the conduit 5 to the air shaft 4, it moves against and actuates the rotor 9 so that the rotating pulley 11 can be utilized for transmitting motion to any mechanism which it may be desired to actuate.

By providing a shield 17 of the peculiar shape shown and described, it will be seen that it will prevent downwardly moving currents of air from pushing back the air currents rising through the air shaft 4. Furthermore, when air currents are moving upwardly or horizontally under the shield 17, portions of them will strike the inner surface of the shield and thus whirl around under the shield, thus creating a supplemental suction upwardly through the hood.

What is claimed is:—

The combination with an air receiving casing, an upwardly extending air shaft, a flue connecting the casing with the lower portion

of the shaft, a rotor within the flue, of arms fixedly connected to the air shaft and extending upwardly therefrom, an imperforate semi-spherical dome-like shield supported by the arms and over the air shaft, a hood mounted for rotation upon the upper end of the air shaft and below the shield, and a vane carried by the hood and located under and projecting into the semi-spherical shield and in the path of a direct current of air passing between the air shaft and the shield, to hold the outlet of the hood out of the wind, said shield constituting means for creating a whirling action of a portion of the air current passing under the shield.

In testimony that I claim the foregoing as my own, I have hereto affixed my signature in the presence of two witnesses.
